OSCILLATING SANDER

Kenneth C. Atkin, Muskegon, Mich., assignor to
 Clarke Sanding Machine Company, Muskegon,
 Mich., a corporation of Michigan

Application September 9, 1950, Serial No. 183,920

3 Claims. (Cl. 51—170)

1

This invention relates to surface treating machinery, and has specific reference to a portable oscillating sander having a motor driven, vibrating abrasive or polishing element adapted for free manipulation over a surface for smoothing and fine finishing.

There has long been a recognized need for small, portable sanding and polishing machines, and many types of machines intended for this purpose have been proposed in the past. It has become fairly well known, however, that these prior art machines fall far short of full accomplishment of their intended purpose and include undesirable features which render them unsatisfactory in one respect or another. In most cases the machines have been so designed and constructed that the entire machine, including the handle portions or hand grips thereof, were subject to extreme vibration, rendering the machine hard to control and very tiring to the operator when in use. Also, in many cases, the machines have lacked durability and have been too short-lived to be commercially practicable. In addition, they have displayed a tendency to rattle, overheat, and to break down or shake themselves loose within a very short period of operation. The more elaborate machines designed to overcome these objectionable tendencies have been so inherently complex and expensive as to be unsalable in a highly competitive market.

It is, therefore, the general aim of the present invention to provide an improved oscillating sanding machine wherein the defects inherent in previously known machines of this general type are overcome, and to provide a simple, durable, low cost machine which is at the same time efficient, quiet, and easy to use.

A specific object of the invention is to provide an oscillating sander so designed and constructed as to impart energetic vibrating movement to the sanding pad, yet to do so in such a manner as to largely eliminate vibration of the other parts of the machine, particularly the motor housing and handles by which it is manipulated.

Another object of the invention is to provide a machine as indicated above including an auxiliary motor cooling fan disposed externally of the motor housing, so that the motor housing may be maintained at a temperature low enough that it is not uncomfortable to handle, notwithstanding that the machine is driven by a motor of conventional design and is operated under full load.

A further object of the invention is to provide an oscillating sander having a sanding pad to

2

which a motor imparts reciprocating or vibrating movement, with a unique, counterweighted fan disposed between the motor and the sanding pad and serving the double function of eliminating vibration of the motor housing and handles, and supplementing the cooling effects of the internal cooling system of the motor. A still further object of the invention is the provision of an improved driving mechanism for an oscillating surface treating machine, wherein end thrust on the motor shaft crank and bearings is entirely eliminated. This is of marked advantage in several respects. For one thing, it minimizes wear on the bearings of the motor and permits the use of a motor having no end thrust bearings without sacrifice of long life of the machine. Moreover, it reduces wear and friction in the crank pin and bearing which convert the rotary motion of the motor into oscillating motion in the sanding pad. These effects result in eliminating undue friction throughout the moving parts, and thus result in a more efficient utilization of the power of the motor in driving the sanding pad. A still further advantage inherent in the construction employed to accomplish this object is that the need of maintaining extremely close tolerances is eliminated. In fact, considerable latitude in the fitting of parts may be permitted without disadvantageous effects.

Another important object of the invention is the provision of a machine wherein the sanding pad, motor housing and fan are so related with respect to each other that the air utilized to cool the motor is discharged away from the work and dissipated into the open air, rather than being allowed to blow across the surface being treated. This is of advantage in that it results in a machine capable of operation with much less dust than developed by other types. It also results in more efficient abrasive action, since any grit or sand dislodged from the sanding pad is not blown away, but remains on the surface being treated and continues to function as an abrasive agent thereon.

A further object of the invention is the provision of a portable motor driven sanding machine wherein the sanding pad is directly driven by a crank on the motor shaft and is mounted by improved yieldable mounts, which permit vibratory movement of the pad in any lateral direction without undue noise or rattle, yet afford adequate support to maintain the fixed spacing desired between the motor housing and the pad.

The foregoing objects are accomplished in the present teaching by a relatively simple mechanism consisting essentially of a motor with a

small crank pin directly coupled to the center of a vibratory sanding pad, with a plurality of flexible rubber mounting studs supporting the pad from the motor, and a counterweighted fan positioned between the motor and the pad serving the double function of cooling the motor and compensating for the inertia of the sanding pad to reduce vibration of the motor and handles thereon.

A preferred embodiment of the present invention is illustrated in the drawings of the present specification, wherein:

Figure 1 is a plan view of a sanding machine according to this invention;

Figure 2 is a side elevational view thereof, shown partially in section along the plane of the line 2—2 of Figure 1;

Figure 3 is an enlarged detail plan sectional view taken substantially on the plane of the line 3—3 of Figure 2;

Figure 4 is an enlarged detail sectional view taken substantially on the plane of the line 4—4 of Figure 2 and illustrating the flexible rubber mountings for the sanding pad; and

Figure 5 is a side elevational view of the counterweighted fan employed herein.

The sanding machine disclosed herein comprises a relatively flat sanding pad 10 mounted on a frame which consists of a motor housing 11 attached to a flanged stamping 12 and provided with outwardly extending handles 13 and 14. The motor 11 is vertically disposed, with its armature shaft 15 projecting downwardly through a bearing 16. Air inlets 17 are formed in the upper end of the motor housing, and coacting air outlets (not shown) are located at the lower end of the housing adjacent the bearing 16. Ordinarily, small motors of the type utilized herein include an internal fan to prevent overheating, and in the preferred embodiment of this invention, as manufactured, such a fan is included within the motor housing as indicated at 18, although, as will appear more fully hereinafter, it has been found desirable to supplement the action of the internal motor fan by other cooling means, so that the motor housing is maintained at a sufficiently low temperature that it may be handled by the operator without discomfort, even after long continued use of the machine.

The sheet metal stamping 12 is secured to the lower end of the motor by a number of machine screws 19, and a resilient rubber gasket 20 is interposed between the stamping and the motor housing so as to provide a firm, vibrationless joint between the parts, so that these parts, with the handles 13 and 14, form a unitary frame for the machine. The handle 14 includes a switch 21 and serves as a connection for a line cord 22 to which the motor leads 23 are connected.

The flanged stamping 12 is of generally rectangular shape and is perforated adjacent its four corners to receive the upper ends of a plurality of flexible rubber mounting posts 24. Each of these plugs is of solid rubber, consisting of a generally cylindrical lower section 25 connected to a grooved top section 26 by a reduced neck portion 27. The lower sections 25 are provided with molded-in inserts 28 threaded to receive machine screws 29, by which the lower ends of the mountings are secured to the flat sheet metal backing plate 31 of the sanding pad 10. As shown, the sanding pad has a resilient rubber facing 32 under the metal backing plate 31.

The sanding pad 10 is positively driven from

the motor shaft 15 by means of an offset crank 34 having a sleeve portion 35 fitted over the end of the motor shaft. The sleeve portion 35 of the crank also carries a counterweighted fan 36, the hub 37 of which is secured to the sleeve and motor shaft by means of set screws 38 and 39.

The fan 36 includes a plurality of curved radial fins 41 extending upwardly from a circular disc or plate which is relatively thin on one side of the fan as indicated at 42 (Figure 5), but is of considerably greater thickness in the portions 43 on the other side, so that the fan is effective as a counterbalance for the crank pin 34. The counterweighted fan thus compensates for the inertia effects of the sanding pad 10, and functions to confine the vibration of the mechanism to this pad and its associated parts, and to substantially eliminate vibration of the frame, motor, and handles.

The lower end of the crank 34 extends into a ball bearing 44 mounted in a cup 45 formed as an integral part of the metal backing plate 31 of the sanding pad. Thus, as the motor revolves, the entire sanding pad 10 is vibrated. The rubber mounting posts 24 yield sufficiently to permit unrestricted lateral movement of the pad in any direction, yet these posts maintain the sanding pad in properly spaced relationship with the motor and the frame stamping 12. The metal backing plate 31 of the sanding pad 10 includes upwardly extending flanges 48 at its ends and side flanges 49 along each side. These flanges add to the rigidity of the pad and at the same time function as air deflectors, so that the air discharged outwardly from the fan 36 is directed upwardly and away from the work. With this arrangement, the blast of air from the fan is dissipated in free air rather than being directed against the working surface, and as a consequence, very little dust is created by the action of the machine. Also, any grit or sand which is dislodged from the sandpaper tends to remain on the working surface and continue its abrasive function, rather than being blown away.

It is contemplated that in the use of the machine a sheet of sandpaper will be secured across the lowermost surface of the rubber facing 32 on the sanding pad 10. Means are accordingly provided to hold the sandpaper sheet in position firmly, yet in a manner such that it may be easily removed and replaced when required.

As illustrated, the sandpaper sheet 51 extends across the bottom of the rubber surface of the sanding pad and has its ends passed upwardly and doubled back around the end flanges 48 of the sanding pad. The free ends 52 of the sheet are held under wire springs 53 pivoted on crosspins 54 and pressed downwardly against the sandpaper by double coil springs 55 carried on the pins 54. Each coil spring 55 has two end portions 56 bearing downwardly against the end portions of the springs 53 and a center portion 57 resting against the upper surface of the metal plate 31 of the sanding pad. The spring 53 has an upwardly off-set bail portion 58 intermediate its ends to facilitate manual lifting of the spring in removing and replacing the sandpaper sheet.

From the above it will be apparent that the present invention provides a vibrating sander which is mechanically simple and relatively inexpensive to manufacture, yet is at the same time durable, quiet and efficient. It is to be particularly noted that the sander here disclosed accomplishes a positive mechanical drive from the motor to the sanding pad, yet includes a counter-

weight so disposed as to compensate for the inertia of the pad and its associated parts, so that the pad will be energetically vibrated by the motor, but the frame and handles of the device will be relatively free of vibration. This results in a machine that is easy to use, yet is highly efficient in operation.

It is also to be noted that the action of the internal fan ordinarily provided in conventional motors is supplemented by the counterweighted fan of this disclosure in such a manner that cool running of the motor is assured, and it should be further noted that this is accomplished by the same mechanism which compensates for the inertia of the sanding pad and eliminates motor vibration. This is a feature making for simple, rugged, low cost construction.

It is to be further pointed out that the machine is of such design and construction that its operation does not raise an appreciable amount of dust, primarily for the reason that the air used to cool the motor is directed away from the work so that it does not blow dust into the air. The machine is also of such design and construction that friction and unnecessary wear due to end thrust on the motor shaft or crank pin is eliminated, yet the pad is so mounted as to move freely in any lateral direction. Moreover, the resilient character of the rubber mounting pads eliminates noisy metal parts and has an inherent capacity for silencing the mechanism so that there is no tendency toward chattering or rattling.

Having thus described my invention, what I claim as new and desire to secure by United States Letters Patent is:

1. In a sanding machine, the combination of a frame, a vibratory sanding pad, and laterally yieldable mounting means consisting of a plurality of independent rubber posts interconnecting the sanding pad with the frame; said frame including a motor having a rotary driving shaft disposed perpendicularly to the sanding pad with a crank pin on said driving shaft in operative engagement with said sanding pad and an eccentric counterweight secured to the driving shaft adjacent the crank pin to compensate for the inertia of the sanding pad and reduce vibration of the motor housing; said counterweight including a centrifugal fan positioned adjacent one end of the motor and adapted to draw air therethrough, with upwardly directed flanges along the marginal edges of the sanding pad to direct the air discharged from the fan upwardly and outwardly away from the work.

2. In a sanding machine, the combination of a frame, a vibratory sanding pad, and laterally yieldable mounting means consisting of a plu-

rality of independent rubber posts interconnecting the sanding pad with the frame; said frame including a motor having air inlet and outlet ports and an internal fan constructed and arranged to draw ambient air through said motor; with a crank pin on said driving shaft of said motor in operative engagement with said sanding pad; together with an eccentric counterweight secured to the driving shaft adjacent the crank pin to compensate for the inertia of the sanding pad and reduce vibration of the motor housing, said counterweight including a centrifugal fan positioned immediately adjacent the air outlet ports of the motor and adapted to augment the action of the internal fan to draw additional air therethrough, with upwardly directed flanges along the marginal edges of the sanding pad to direct the air discharged from the fan upwardly and outwardly away from the work.

3. In a sanding machine, the combination of a frame, a motor thereon, a vibratory sanding pad, and a plurality of separate flexible mounting members spaced apart from each other and interconnecting the sanding pad with the frame; said mounting members each consisting of a rubber post yieldable in at least two lateral directions to permit unrestricted lateral vibratory movement of said pad with respect to the frame; with a rotary driving shaft extending from the motor to the pad and disposed perpendicularly to the sanding pad, and a crank pin on said driving shaft directly engaging an anti-friction bearing fixed to said sanding pad; together with an eccentric counterweight secured to the motor shaft adjacent the crank pin to compensate for the inertia of the sanding pad and reduce vibration of the motor housing, said counterweight including a centrifugal fan adjacent one end of the motor housing to draw air therethrough and upwardly directed flanges around the periphery of said pad adapted to direct the air from said fan upwardly and outwardly away from the work.
